UNITED STATES PATENT OFFICE

HARRY B. HULL, OF DAYTON, OHIO, ASSIGNOR TO FRIGIDAIRE CORPORATION, OF DAYTON, OHIO, A CORPORATION OF DELAWARE

REFRIGERATING APPARATUS

Application filed June 30, 1928. Serial No. 289,550.

This invention relates to refrigerating apparatus and more particularly to a water cooler provided with a water cooling compartment, a freezing compartment and a food or bottle storage compartment.

An object of this invention is to provide a water cooler, which may be of the self-contained type, which water cooler is provided with an ice cube freezing compartment and 10 with a compartment suitable for receiving bottles of beverage or small amounts of food.

Another object of this invention is to provide a water cooler of the type hereinbefore 15 mentioned in which the food or bottle cooling compartment may be maintained at a sufficiently low temperature.

Another object of this invention is to provide a water cooler having a water cooling 20 compartment, a food or beverage cooling compartment and an ice cube forming compartment which is refrigerated by an expansion coil in such a manner that the coldest portion of the coil is available for freezing the 25 ice cubes, and a warmer portion is available for cooling the water.

Another object of this invention is to provide a water cooler having water and beverage cooling compartments and an ice cube 30 freezing compartment, and in which the evaporator is so disposed that proper temperatures are maintained in the various compartments.

Further objects and advantages of the 35 present invention will be apparent from the following description, reference being had to the accompanying drawing, wherein a preferred form of the present invention is clearly shown.

40 In the drawings:

Fig. 1 is a view partly in elevation and partly in section of the side of a water cooler embodying features of my invention;

Fig. 2 is a view similar to Fig. 1 taken at 45 right-angles to Fig. 1.

Fig. 3 is a cross sectional view, with partial diagrammatic showings, of a modified form, and

Fig. 4 is a cross sectional view taken at 50 right angles to Fig. 3.

A water cooler embodying features of my invention may comprise, in general, a water cooling compartment generally designated as 20, a food or bottle cooling compartment, generally designated as 21, and an ice cube 55 freezing compartment generally designated as 22.

These compartments are adapted to be refrigerated by suitable refrigerant circulating means. In this particular embodiment, the refrigerating means may comprise an expansion coil generally designated as 23. An expansion valve 24 may be placed in the rear of the ice cube forming compartment 22 and the portion of the coil 23 immediately following the expansion valve may be wound around the outside of the ice cube forming compartment. From thence the expansion coil may be wound around the water cooling compartment 20 and may be provided 70 with an outlet pipe 25.

A refrigerant liquefying unit may be placed in any convenient location. For instance it may be placed in the lower half of the cabinet. It may be of the well-known compressor-condenser-receiver type and may deliver the liquid refrigerant through the pipe 27 to the expansion valve 24. From thence the refrigerant passes through the portion 23a of the coil 23 which surrounds the ice cube forming compartment 22. From thence it passes through the section 23b which surrounds the water cooling compartment 20 and returns through the pipe 25 to the refrigerant liquefying unit.

If the water cooler is to be of the demijohn type, it may be provided with a suitable opening 28 and the proper gasket 29 for receiving the demijohn 30. A suitable faucet 31 may be connected to the water cooling compartment. A suitable drain tank 32 may be attached to the cabinet underneath the faucet 31 and may be provided with a suitable drain plug 33.

The freezing compartment may be provided with an ice tray of the usual type having ice cube forming sections, not shown, and provided with a handle 34 for removing the ice tray from the ice tray compartment 22.

It is thus seen that the refrigerant imme- 100

diately after being expanded in the expansion valve 24 is immediately conducted to the freezing compartment 22 so that the coldest portion of the coil is in contact with the freezing compartment. Thus the coldest portion of the coil is used to provide the necessary refrigeration for freezing the ice cubes. This same portion of the coil is also used to cool the air in the food or beverage storage compartment 21 and thus a sufficient amount of refrigeration is provided in this compartment. After furnishing the necessary refrigeration for the compartments 21 and 22 the coil delivers its remaining refrigeration to the water cooling compartment 20 which does not require such a cold temperature as the other compartments, in order to deliver drinking water at its most palatable temperature.

The cabinet may be of any improved design. For instance it may comprise a suitable metal frame-work 40 on which suitable side panels 41 are attached. A wooden frame-work 42 may be placed at the top of the metal frame-work 40 and the water cooling compartment 20 may be provided with flanges 43 adapted to rest on the wooden frame-work 42. A suitable door 44 may be hinged to the cabinet and is adapted to swing into the door jamb generally designated as 45. The covers 46 and 47 may have telescoping sections to receive the demijohn and may be readily removable in order to enable the compartment 20 to be readily cleaned. Suitable insulation 48 may be provided, and if desired this may be attached to the linings of compartments 20 and 21 with bituminous cement or the like. The insulation around the portion 23b may be suitably recessed either vertically or spirally to receive the coils of the section 23b. The linings of the compartments 20 and 21 may be welded together where they join. Thus in the preferred form, the compartments 20 and 21 are in vertical alignment and are of substantially the same vertical extent, providing a long, narrow, upright and stream line cabinet.

If desired, this cabinet may be made for connection to the water plumbing system of the building. If so desired, the character of the covers 46 and 47 may be changed by omitting the opening for the demijohn and a suitable float valve controlled mechanism may be provided for controlling the admission of water from the plumbing system into the compartment 20. Thus as shown in Figs. 3 and 4, a water cooler may be provided with compartments 20a, 21a and 22a substantially similar to those shown in Figs. 1 and 2, but modified for attachment to a water plumbing system. Thus the cover 46a may be provided with a closure 60 adapted to rest at the place where the gasket 29 was originally placed. Otherwise the covers 46a and 47a may be identical with the covers 46 and 47 of Figs. 1 and 2. The connection with the water plumbing

system may include a pressure pipe 61 leading to a valve 62 controlled by means of the float 63. Thus the float 63 maintains a substantially constant level of liquid in the compartment 20a. An overflow pipe 64 may be connected to a conduit 65 surrounding the pipe 61. Thus failure of the float control will cause the water to flow out through the pipe 64 and conduit 65 to a suitable connection with a drain. Under normal conditions the conduit 65 contains nothing but air and thus the air acts as an insulator for the pipe 61 and prevents accidental freezing of the pipe 61 if the water in the compartment 20a should become frozen.

A refrigerant liquefying unit may be placed in the lower compartment 66. This unit may be of any suitable type. Thus as shown diagrammatically in Fig. 3, the unit may include a compressor 67 delivering compressed refrigerant to the condenser 68 which delivers the condensed refrigerant to the receiver 69. From thence the liquid refrigerant is delivered through the pipe 27a to the expansion valve 24a which corresponds to the valve 24 of Figs. 1 and 2. The coil around the compartment 22a and the compartment 20a may be substantially as shown in Figs. 1 and 2 and from thence the expanded refrigerant may return through the pipe 25a to the compressor 67. Suitable driving means for the compressor may include an electric motor 70.

A suitable automatic control, responsive to conditions in the refrigerating system, may be provided. Thus, such a control may include a thermostatic bulb 71 connected by means of the conduit 72 to an expansible bellows 73. The expansible bellows 73 may operate a suitable snap switch 74 which controls the starting and stopping of the motor 70.

The operation of the refrigerating system may be entirely automatic. For instance, the expansion valve 24 may be of the automatic pressure-regulated type, preferably responsive to the pressure in the coil 23. The operation of the refrigerant liquefying unit may also be automatic. If desired a suitable thermostat, not shown but similar to that shown in Figs. 3 and 4, may be placed in any one of the compartments 20, 21, or 22, preferably in close thermal relation to the coil 23, and this thermostat may control the operation of the refrigerant liquefying unit. If the refrigerant liquefying unit is of the electric motor driven type, the thermostat may operate a snap switch which may control the starting and stopping of the electric motor similarly to the modification shown in Figs. 3 and 4.

While the form of embodiment of the invention as herein disclosed, constitutes a preferred form, it is to be understood that other forms might be adopted, all coming within the scope of the claims which follow.

What is claimed is as follows:

1. A water cooler having a water cooling compartment, a freezing compartment, a food storage compartment, an expansion coil in thermal contact with the freezing compartment at a zone near its expansion point and in thermal contact with the water cooling compartment at a zone farther removed from said expansion point. 5
2. A water cooler having a water cooling compartment, a freezing compartment, a food storage compartment, an expansion coil in thermal contact with the freezing compartment at a zone near its expansion point and in thermal contact with the water cooling compartment at a zone farther removed from said expansion point, said coil also being in thermal contact with said food storage compartment. 10
3. A water cooler comprising a water compartment adapted to receive a demijohn, a food storage compartment below said water compartment, an expansion coil having an expansion valve, a freezing tray compartment in said food storage compartment, said expansion coil surrounding said tray compartment and having a portion farther removed from said expansion valve surrounding said water compartment. 15
4. A water cooler comprising a water compartment, a food storage compartment below said water compartment, an expansion coil having an expansion valve, a freezing tray compartment in said food storage compartment, said expansion coil surrounding said tray compartment and having a portion farther removed from said expansion valve surrounding said water compartment. 20
5. A water cooler comprising a water compartment, a food storage compartment in alignment with said water compartment, an expansion coil having an expansion valve, a freezing tray compartment in said food storage compartment, said expansion coil surrounding said tray compartment and having a portion farther removed from said expansion valve surrounding said water compartment. 25
6. A water cooler having a water cooling compartment, a faucet connected to said compartment, a freezing compartment, a food storage compartment, an expansion coil in thermal contact with the freezing compartment at a zone near its expansion point and in thermal contact with the water cooling compartment at a zone farther removed from said expansion point. 30
7. A water cooler having a water cooling compartment, a faucet connected to said compartment, a freezing compartment, a food storage compartment, an expansion coil in thermal contact with the freezing compartment at a zone near its expansion point and in thermal contact with the water cooling compartment at a zone farther removed from said expansion point. 35
8. A water cooler comprising a water compartment adapted to receive a demijohn, a faucet connected to said compartment, a food storage compartment below said water compartment, an expansion coil having an expansion valve, a freezing tray compartment in said food storage compartment, said expansion coil surrounding said tray compartment and having a portion farther removed from said expansion valve surrounding said water compartment. 40
9. A water cooler comprising a water compartment, a faucet connected to said compartment, a food storage compartment below said water compartment, an expansion coil having an expansion valve, a freezing tray compartment in said food storage compartment, said expansion coil surrounding said tray compartment and having a portion farther removed from said expansion valve surrounding said water compartment. 45
10. A water cooler comprising a water compartment, a faucet connected to said compartment, a food storage compartment in alignment with said water compartment, an expansion coil having an expansion valve, a freezing tray compartment in said food storage compartment, said expansion coil surrounding said tray compartment and having a portion farther removed from said expansion valve surrounding said water compartment. 50
11. A water cooler comprising a long, narrow, and stream line cabinet, said cabinet including an insulated water cooling compartment, an insulated food storage compartment, said compartments being of substantially the same horizontal dimensions and vertically aligned, a water freezing compartment in said food storage compartment, said compartments being provided with means for expanding a refrigerant, and a refrigerant liquefying unit in said cabinet and connected with said means for expanding refrigerant. 55
